In Germany January 3, 1938

15 Claims. (Cl. 179—26)

Circuit arrangements for automatic telephone installations having several offices in tandem.

The invention relates to automatic telephone exchanges having several tandem offices in which the called stations are reached over the lines set up by preliminary selectors and in which the connecting lines forming a desired connection are selected by the transmission of dialled pulses over the junction lines to selectors.

In such installations it is immaterial whether one or several junctions intervene between the calling and called stations so long as these lie in the desired direction.

In this connection there are several known arrangements in which by the dialling of a designating digit the switching apparatus seized by the calling line becomes effective and in which through switching in the selector after it has been set in accordance with the designating digit from the calling line or in which the setting of the same by a designating digit from the calling line is prevented and a revertive switching of the connection via the call finder which has been set on the terminals of the calling line is effected. These arrangements require the provision of a considerable amount of equipment since the normal operation of the selector is interfered with and a revertive connection at the call finder must be undertaken.

Further, arrangements have become known in which the revertive switching, after the release of the foregoing selectors, is prevented since by dialling the designating digit the selectors are set over the calling line. Here also considerable equipment is involved which is taken up in the test circuit in order that the line from the call finder to the accompanying line selector is free and the remaining lines appear busy while at the same time other line selectors appear busy to the calling line.

Other arrangements have been proposed in which the setting of the selector by the calling line is, on a revertive call in the calling sub-group, made possible in that each junction line is joined to two contacts in the selector contact bank. In the speaking contact banks these two contacts are connected together, while in the test contact bank one of them is connected to a corresponding contact in the preselector switch and the other contact to the usual test wire to determine the condition of occupancy. If a revertive call is being set up the stoppage of the selector on the terminals of the calling line is effected by the first contact of the test contact bank in dependence on the designating digit through the

preselector, while by the setting up of other connections, the stoppage of the selectors is effected in dependence upon the usual testing process on a free line of the designated traffic direction.

5 The present invention covers another method in which without revertive switching via the pre-selector apparatus, the calling line is utilized for setting up revertive calls. This is attained by making effective the control of the selectors through current pulses corresponding to the pre-ordained exchange which permits the positioning of an auxiliary selector in the taking route to the pre-ordained exchange by means of a preselecting switch controlled by the designating digit.

10 Figs. 1, 2A and 2B show an example of one method of carrying the invention into effect.

Fig. 1 shows a semi-automatic system chosen to illustrate the features of the invention. It consists of three sub-offices U1, U2 and U3 and a main exchange HA. The sub-exchanges U1 and U3 are in tandem to the subexchange U2 and reach this via the main exchange HA in which there is an operator who effects the necessary connections between the subscribers of the individual sub-exchanges. In place of an operator, full automatic operation can be arranged for in the main exchange HA and a storage equipment provided there which receives the dialled pulses from the sub-exchanges and then builds up the required connection.

15 Figs. 2A and 2B show the switching technicalities of the schematic diagram of Fig. 1 for the sub-office U2 and especially the two selecting means consisting of a call-finder AS and line selector LW with an auxiliary selector EW.

20 As can be seen from Fig. 1, in the sub-exchange U1 selective means are provided of which only the call finder AS1 and the line selector LW1 are shown. From these two selectors connecting lines a1/b1 and a2/b2 branch to the sub-exchange U2 and end there in the contact banks of the call finder and line selector (AS/LW) selector pair. To the contact banks of this pair of selectors are attached the lines coming from the sub-exchange U1 and the lines from the sub-exchange U3 as well as the lines from the individual subscribers, the different groups of lines terminating in different levels of the line selector LW.

25 The individual subscribers are connected to the first level while in the third level the lines to the sub-exchange U3 are connected. The junction lines are then connected to a supplementary, auxiliary, selector EW which serves for the so-called revertive calling in the called sub-exchange group and on which the junction lines are con-

nected for the purpose of making possible the further connection in the next sub-exchange.

From the sub-exchange U_2 junction lines ao/bo are led from the switching selector AW to the main exchange HA . Obviously the number of selector pairs in the individual sub-exchanges and the junction lines between these as well as the individual sub-exchanges and between the sub-exchange U_2 and the main exchange HA can be varied according to requirements.

If a subscriber such as Tn_1 of sub-exchange U_1 in such a system calls then, first, in known manner a free call finder, say AS_1 is set in operation and places itself on the calling subscriber's lines connecting him to the sub-exchange U_2 over a junction line such as a_2/b_2 . This operation is now effective in the sub-exchange U_2 and causes the operation of a further free call finder such as AS . This sets itself on the junction line a_2/b_2 over which the call has been received. When AS comes to rest, a switching selector such as AW sets itself on a free junction line to the main exchange HA in readiness for the call to the operating position there. The call signal is now received. The operator plugs in in the usual way into the jack which is indicated and replies to the calling subscriber. If the subscriber Tn_1 has not waited for the through connection to the main exchange HA , he is called by the operator over the route which has been built up. The calling subscriber can only attain a connection through the action of the operator at the main exchange with the subscribers of any network or, after suitable adjustment of the line selector LW in the sub-exchange U_2 with subscribers of this exchange or by control of the line selector LW and further control of the line selector LW_2 with a subscriber of the sub-exchange U_3 respectively, or by control of the line selector LW and auxiliary selector EW and subsequent adjustment of line selector LW_1 with a subscriber in his own sub-exchange. In the last case the line selector LW is set by means of a designating digit to the first contact of a certain level to which are connected the junction lines a_2/b_2 between sub-exchange U_1 and U_2 . There is no hunting operation and the auxiliary selector is set in operation by means of the call finder AS reached by the designating digit and the connection is switched through to the line selector LW_1 .

By setting the auxiliary selector EW the possibility is offered, in cases where only one junction line is available between sub-exchanges U_1 and U_2 , to build up a revertive connection to the sub-exchange U_1 , or if several junction lines are available between these exchanges for the revertive connection to be formed over the line seized for the call and thus obviate the use of a second junction line.

This so called revertive selection in the calling sub-exchange or in the calling sub-exchange group with several tandem sub-exchanges is now described by means of Figs. 2A and 2B.

If subscriber Tn_1 of U_1 (Fig. 1) calls (lifts telephone off hook operates a magnet or key, etc.) a free call finder in U_1 such as AS_1 is started which hunts to find the calling subscriber Tn_1 .

If, at this instant, there is no free call finder, then, in known manner, the call is stored which, on a call finder becoming free starts this up.

After the call finder AS_1 has found the calling subscriber Tn_1 , the latter is connected over the junction line a_2/b_2 to the sub-exchange U_2 . From the sub-exchange U_1 an alternating current

impulse is sent over the wire b_2 which energizes relay R through its winding 1 . Relay R locks up by the closure of its contact $1r$ and via this contact and the contact $5t$. If the call finder AS in the sub-exchange U_2 is free then, by closure of contact $12r$ relay M_1 is energized via: earth, battery, relay M_1 , contacts $16sp$, $14g$, $13t$, $12r$, earth. By closure of contact $22mt$, relay S is energized via: earth, battery, relay S , contact $22mt$, earth. 10 Via contact $18s$ a circuit is closed for the rotary magnet of the call finder. This circuit is: earth, battery, rotary magnet Das of AS , contact $20r_1$, $19p$, $18s$, $16sp$, $14g$, $13t$, $12r$, earth. The call finder AS takes one step. By opening contact $21das$ of the rotary magnet Das the short-circuit on winding I of relay R_1 is removed so that R_1 , in a branch to the energizing circuit of the rotary magnet Das , is energized and at its contact $20r_1$ disconnects the circuit of the rotary magnet of the call finder AS . This sets up the known to and fro operation of the rotary magnet of the call finder AS and the relay R_1 , so that the call finder progresses step-by-step, until it reaches the junction line a_2/b_2 which has been seized by the calling subscriber. In this case the following circuit is formed: earth, battery, relay T , contact $9r$, $10t$, winding II of relay R , contact $11r$, wiper c of AS , windings I and II of relay P , contacts $62mt$, $63c_1$, shaft contact $66klw$ of the line selector LW , earth. 15 Relays P and T operate in this circuit while relay R is held energized. By opening of contact $5t$ the call storage arrangement is disconnected while by opening contact $13t$ relays M_1 and R_1 as well as the rotary magnet Das are freed from current. 20 As a result of the opening of contact $22mt$, relay S releases. In the meantime, through the energization of relay P via contacts $44p$ and $45p$, the talking wires are switched through while, during the closure of the contact $60p$, the junction line reached from the call finder AS is busied. By closure of contact $30p$, relay S_2 is energized which now, by the closure of contact $17sp$ prepares the starting circuit for the following call finder (not shown) so that further calls from the subscribers of the sub-exchange U_2 or over the junction lines of other sub-exchanges via a second selector pair of the sub-exchange U_2 can be dealt with. After energization of relay P the following circuit is closed via contact $31p$; earth, battery, resistance Wi_3 , contact $31p$, $32g$, relay An , earth. Relay An operates in this circuit and permits by a method, not here of interest, the starting up of the switching selector AW for the purpose of connecting the selector pair AS/LW seized by the calling subscriber. 25 The test relay PO is connected to the wiper d of the switching selector AW via contact $41an$ so that on obtaining the designated selector pair via contact $31sp$, the following circuit is formed: earth, battery, winding II of relay G , contact $33g$, shaft contact $34lw$ of line selector LW , contact $37sp$, wiper d of the switching selector AW , contact $41an$, windings I and II of the relay PO , earth. Relay G operates in this circuit. At the opening of contact $32g$, the relay An is deprived of current so that further stepping of the selector AW is prevented. Relay PO by short-circuiting of its high resistance winding I via its contact $40po$ busies the selector pair, while by closure of contact $107po$ and $108po$, through switching over the junction line ao/bo takes place to the main exchange HA . In the meantime through previous closure of contact $110an$ at the start of the switching selector AW , alternating current is applied to the wire bo which produces 30 35 40 45 50 55 60 65 70 75

a call signal at the main exchange HA. In place of the main exchange HA a further sub-exchange can obviously be reached over the junction lines *ao/bo* in which case, in the same way as in the sub-exchange U2, the corresponding relay R is energized by alternating current with the same switching process for the purpose of through switching to the main exchange HA lying behind this. Whatever switching process is employed does not matter. Assuming that for the sake of simplicity that in the previous case HA has been reached over the junction lines *ao/bo*, then the calling signal is produced by alternating current. The operator answers by plugging into the jack of the calling line. As a result a circuit (not shown) is formed via the wire *ao* of the junction line for the relay J which operates. By closure of contact 84j, relays C and C1 become energized and lock themselves up by closure of contact 86c in a holding circuit.

If the calling subscriber has waited then, via the loop from the subscriber, a relay corresponding to Y in the sub-exchange U1 is energized and via its contact corresponding to 70y and a choke coil corresponding to Dr2, places battery potential to the wire *b2* by which the relay Y of sub-exchange U2 is energized via: wire *b2*, wiper arm *b* of the call finder AS, contacts 45p, 53u, 55b, 57k, 67e, relay Y, earth. Relay Y at its contact 70y and choke coil Dr2 places a battery potential on the wire *bo* of the junction line so that a signal is given to the operator at the main exchange which indicates that the subscriber has taken his telephone off the hook.

If the calling subscriber has not waited, this battery potential is not applied and the operator receives no signal. The operator calls the subscriber. This back calling is introduced in known manner via wire *bo* in sub-exchange U2 and operates relay E and from there via contact 68e is transmitted to the sub-exchange U1 from which a call is sent out. When the subscriber answers calling current is cut off. The operator answers and can set up any of the already mentioned arrangements.

The following case is of interest for back calling connections. If, by way of example, a calling subscriber Tn1 desires a subscriber in his own sub-exchange U1. The operator must in this case set the line selector LW of the calling sub-exchange by means of the designating digit. There, as shown above, the junction line to the sub-exchange U1 is connected to the second level of the line selector and the designating digit is 2. The operator sends two impulses. These result in the energizing circuit over the wire *ao* including a relay J being twice interrupted. Contact 78j is thereby closed so that the vertical magnet of the line selector receives two current impulses via: earth, battery, vertical magnet H of LW, shaft contact 79wlw of LW, contacts 78j, 77c, earth.

During the transmission of the impulses, relay V is impulsively operated via contact 83j while the slow relay V1 is continuously energized. The line selector LW has a level contact 29dk which is closed every time the line selector is stepped on to a level to whose contacts the junction lines are connected. This level contact is also closed in the previous case so that the following circuit is formed: earth, battery, relay Q, contact 27u, level contact 29dk of LW, earth. Relay Q energizes in this circuit and locks itself up in a holding circuit via its contact 28q.

If at the end of the impulse train, relay V1

releases, then, via contact 75q after the first vertical step of the line selector LW, the shaft contact 71klw of LW is closed and the following circuit is formed: earth, battery, rotary magnet of D of LW, contacts 15q, 14p1, 13r1, 72v1, shaft contact 71klw of LW, earth. Rotary magnet D is energized in this circuit and rotates the selector AW in on to the first level. The rotation of LW closes shaft contact 100wlw so that via this contact and the contact 98p1, relay K is energized. By the closure of contact 54k, relay B is connected to the wire *b2* of the junction line from the sub-exchange U1. Then, as mentioned above, when the subscriber takes his telephone down, battery potential is applied to the wire *b2* and relay B energizes. B locks itself up over its contact 55b independently of contact 58k. In the meantime, by opening of contact 57k, the current to relay Y is interrupted so that this relay also releases. A holding circuit is formed for the relay K at contact 91y which is independent of contact 98p1.

As in the previous cases, the call finder AS is already standing on the junction line from the sub-exchange U1 (line *a2/b2*) and by setting of the line selector LW, a connection in the same direction (revertive call) is designated then, immediately after the first step of the line selector LW, the following circuit is formed: 25 earth, battery, relay T1, contact 104p, wiper d of call finder AS on contact 3, wiper c of the line selector LW and contact 1 of the second level, windings I and II of relay P1, contacts 89v1, 91k, 95b, 94c1, earth. Relays T1 and P1 are energized in this circuit. By the opening of contact 14p1 further operation of the rotary magnet D of LW is prevented. The following circuit is closed by the closure of contact 111t1. Rotary magnet Dew of the auxiliary selector 30 EW, contact 113r1, 112u, 111t1, earth. The rotary magnet Dew operates alternately with relay R1 whose winding II is influenced over contact 195dew of the auxiliary selector for such time until its wiper c has found the contact 3 via the wiper e of the call finder AS. If this is the case, the following circuit is formed: earth, battery, relay U, wiper e of the call finder AS, wiper c of the selector EW, contact 111t, earth. Relay U operates in this circuit and stops the selector 45 EW by opening the contact 112u. By closure of contacts 2u, and 3u, wipers a and b of the auxiliary selector EW are connected to the talking wires so that through switching is effected to the lines *a2/b2*.

55 After switching through contacts 46u and 53u are opened so that the call finder AS is disconnected.

By reason of the switching through of the connecting junction lines from the sub exchange 60 U1 via AS, the relay B connected to the line *b2* is deprived of current. The testing circuit of the call finder AS remains closed so that the relay P is locked up.

In this way it is possible, in cases where the 65 desired connection is not effected, for the operator by special means to release the line selector LW without at the same time releasing the connection which has been built up via the call finder to the operator.

70 By the special means relays J and E are controlled by the operator so that the line selector LW with the auxiliary selector EW (C and C1 deenergized) are released, the call finder however is (contact 65e closed) held in the position in which it has been set.

The operator can then immediately set up an alternative connection without it being necessary for the subscriber to once again set up a path to the operator.

Since, as explained above, in the course of the connection relay U is energized, then by opening of contact 27u, relay Q is released and by closure of contact 92u the holding circuit of relay P1 is maintained independently of contact 95b.

Since after the transmission of the first impulse group from the operator relay J is again continuously energized, then, via contact 51j after through switching via contacts 2u and 3u, a relay corresponding to relay J in the sub-exchange is operated via: earth, battery, resistance Wi2, choke coil Dr3, contacts 51j, 3u, wiper a of the selector EW, wire a2 of the junction line to the sub-exchange U1, a relay corresponding to relay J, earth. In the sub-exchange U1 a switching process is originated similar to that in exchange U2 through the operation of relay J. In a similar manner by the transmission of the next series of impulses through the contact 51j then according to the further operation of relay J in U2, the relay corresponding to J in the sub-exchange U2 is operated, which sets the line selector LW1 (Fig. 1) on the terminals of the desired subscriber's lines. If the test relay of the line selector LW1 finds the desired subscriber free then calling current is sent to him in known manner.

During this time the switching process in sub-exchange U1 corresponds to that which went on before it in sub-exchange U2.

Since the switching arrangements of the selector pair in the sub-exchange U1 apart from the auxiliary selector EW, which is not available here, are the same as for the sub-exchange U2 they are shown by Fig. 2.

When the called subscriber replies a relay corresponding to relay Y in the sub-exchange U1 is energized from the subscriber's loop and over a contact corresponding to 70y places battery potential to the wire b2 so that in the sub-exchange U2 over this wire and the wiper b of selector EW relay Y is operated which, at contact 70y applies battery potential to the wire bo and in this way announces to the main exchange HA that the subscriber has replied. The operator now withdraws the plug from the jack and relay J in sub-exchange U2 becomes de-energized. The closure of contact 83j energizes relays V and VI via: earth, battery, relays V and VI, contacts 85s, 83j, 80c, earth. By closure of contact 82v relay C becomes short-circuited so that through opening of the contact 80c, relay C1, V and VI are deenergized.

At the opening of contact 94c1 relays P1 and T1 and by the opening of contact 111t1, relay U, all release.

At the closure of contact 74p1 results, in known manner, the release of line selector LW, while the auxiliary selector EW stays in the position in which it was set for building up the connection.

During the time which lies between the opening of the shaft contact 35klw and the closure of the shaft contact 34wlw of the line selector LW, relays G and PO are without current so that the line ao/bo leading to the main exchange becomes free. The call finder AS by opening of the contact 64c1 and the second deenergization of relay P becomes free for a further call. Simultaneously relays R and T are deprived of current.

Since, in the sub-exchange U1, the opening of contact 51j in sub-exchange U2 also breaks the circuit for the relay U1 corresponding to relay J in U2, this also releases so that via a contact corresponding to contact 83j, a relay corresponding to relay V is energized. Since in U1 a relay corresponding to relay S is, on the subscriber replying, energized over a contact corresponding to contact 24y and held over another contact corresponding to contact 23s, further switching processes are not initiated so that in U1 the selector pair consisting of line finder AS1 and the line selector LW1 remain busy. These are only released when the conversation is ended.

From the foregoing description it will be seen that by the transmission of a current pulse train by means of which a junction line is designated, the line selector is lifted to a level to which the junctions for this direction are connected. At the termination of this pulse train, the line selector rotates automatically. If the call is a revertive one, the line selector LW is held on the first contact of the level which is marked by the call finder AS. The auxiliary selector EW sets itself upon the line which passes via the wiper e. After this the wipers a and b of the auxiliary selector are taken to the talking wires via wipers a and b of the line selector LW.

The auxiliary selector can also be arranged so that it is not connected to the line selector wipers but is in series with these in that all the first contacts of the junction line level in the talking circuit banks are connected to one another and to the wipers a and b of EW.

A revertive call is then effected in the same way as above in that the line selector after it has been positioned on the first contact of the selector EW runs on until it reaches the contacts marked by the call finder AS and switches the connection through over its wipers.

If the line selector LW, on receipt of a designating digit, is positioned on the terminals of another sub-exchange, say U3, then after the vertical motion there is, in the same way, an automatic hunting process.

The line selector does not come to rest on the first contact of the third level since its wiper c does not find this contact marked by wiper d of call finder AS but by operation of its rotary magnet alternately with winding II of relay R1 (contacts 13r1 and 101d) is moved on until its test relay P1 finds a free line, say a3/b3, to the sub-exchange U3. The following circuit is then formed: earth, battery, the relay corresponding to the relay T, a contact corresponding to the contact 8r, test wiper c3, wiper c of the line selector LW, windings I and II of relay P1, contacts 89v1, 91k, 95b, 94c1, earth.

At the opening of contact 74p1, LW stops on this line and through switching is effected via contacts 86p1 and 87p1. The remainder of the switching process goes on in known manner.

On revertive calls in the called sub-office group, by the operation of the line selector which corresponds to the position of its call finder, the line selector steps on the first contact of the designated level and sets its auxiliary selector in operation which, in dependence on the already positioned call finder resulting from the line seized by the call, while, on the contrary, by selection of other traffic directions dependent upon the usual test processes from the line selector, a free junction in the desired direction is sought.

What is claimed is:

1. In a telephone or like system, a plurality of lines, two switches having access in common to said lines, means for seizing one of said switches and transmitting thereto trains of impulses, said one switch responsive to said impulses either to seize one of said lines or to cause the other of said switches, instead of said one switch, to seize one of said lines, depending upon the number of impulses in said train.

2. In a telephone or like system, a plurality of groups of lines, two switches having access in common to said groups of lines, means for seizing one of said switches and for transmitting thereto impulses designating one of said groups of lines, said one switch responsive to said impulses at times to seize a line of the designated group, and said one switch responsive to said impulses at other times to cause the other of said switches, instead of said one switch, to seize a line of the designated group.

3. In a telephone system, a plurality of groups of lines, switching apparatus including two switches having access in common to said lines, means for characterizing any one of said lines, means for thereafter transmitting to said apparatus impulses designating any desired one of said groups of lines, means effective whenever the designated group is the group of which the characterized line is one to thereupon cause one of said switches to connect with said characterized line, said last means effective whenever the designated group is not the group of which the characterized line is one to thereupon cause the other of said switches to search for and seize an idle line in the designated group.

4. In a telephone system, an automatic switch whose wipers have access to a plurality of groups of lines, means responsive to a call on any of said lines for marking in said switch the group of which the calling line is one, means for thereafter directly operating said switch to cause its wipers to search for a free line in a desired one of said groups, and means preventing said wipers from performing said search whenever said desired group is the one marked in said switch.

5. In a telephone system, an automatic switch having access to a plurality of groups of lines, means responsive to a call on any of said lines for extending a connection from the calling line to said switch, means for thereafter directly operating said switch to cause same to search for and seize an idle line in any group except the group of which said calling line is one, and means for preventing said switch from performing said search if directly operated to the group of which said calling line is one.

6. In a telephone system, an automatic switch having access to a plurality of groups of lines, means responsive to a call on any of said lines for extending a connection from the calling line to said switch, means for thereafter directly operating said switch to cause same to search for and seize an idle line in any group except the group of which said calling line is one, means for preventing said switch from performing said search if directly operated to the group of which the calling line is one, and a second switch operated only if said first switch is directly operated to the group of which the calling line is one to search for and seize said calling line.

7. In a telephone system, a plurality of groups of lines, a link circuit, a finder switch in said link effective responsive to a call on any of said lines

to seize the calling line, means for thereafter transmitting to said link impulses designating any one of said groups of lines, a switch in said link having access to said lines and effective

5 whenever the designated group is the group of which the seized line is one to search for and connect with said seized line, and another switch in said link also having access to said lines and effective whenever the designated line is not the 10 group of which the seized line is one to search for and seize an idle line in the designated group.

8. In a telephone system, a plurality of groups of lines, a link circuit including a numerical switch and a non-numerical switch both having access to said lines, said non-numerical switch responsive to a call on any of said lines to seize the calling line and to characterize, in said numerical switch, the group of which the calling line is one, means for thereafter directly operating said numerical switch to cause same to search for an idle line in a desired group, means operated if said desired group is the group characterized to prevent said numerical switch from performing said search, and an auxiliary switch in said link having access to said lines and controlled by said last means only if the desired group is the group characterized to search for and connect with the calling line.

9. In a telephone system, a two-motion switch, 30 lines terminating in different levels of the contact bank of said switch, means responsive to a call on any of said lines for characterizing the level in which said line terminates, means for thereafter directly operating the wipers of said switch to any desired level, said wipers normally effective thereupon to search for an idle line in the desired level, and means preventing said wipers from performing said search if said desired level is the one characterized.

10. In a telephone system, a main exchange, a sub-exchange, a tandem exchange, means controlled by the initiation of a call by a subscriber in the sub-exchange for extending a connection from the sub-exchange to the main exchange 45 through said tandem exchange, means for thereafter transmitting impulses over said connection from the main exchange to the tandem exchange to control the extension of the call to a desired line, a switch in said tandem exchange inoperative if said desired line terminates in said tandem exchange, means for operating said switch to seize said connection if said desired line terminates in said sub-exchange, and switching apparatus in the sub-exchange thereafter controlled 55 over said connection and said switch from the main exchange to complete the call to the desired line.

11. In a telephone system, a first exchange and a second exchange connected by trunk lines, 60 means controlled by the initiation of a call by a subscriber in the first exchange for extending a connection from the first exchange to the second exchange over one of said trunk lines, a switch in said second exchange thereafter operated only if it is desired that the call terminate in said first exchange, said switch effective at said times to automatically connect with said one trunk line, and means for transmitting impulses over said switch and said one trunk line to control switching apparatus in said first exchange to complete the connection.

12. In a telephone system, a first exchange, a second exchange, means controlled by the initiation of a call by a subscriber in the first ex-

change for extending a connection from the first exchange to the second exchange, means for at times further extending said connection to a called line in the second exchange, a switch in said second exchange non-operative at said times, means for at other times controlling said switch to seize said connection, and means for transmitting impulses over said switch and said connection to said first exchange at said other times to control the completion of the call to a called line in the first exchange.

13. In a telephone system, a first exchange, a second exchange, means controlled by the initiation of a call by a subscriber in the first exchange for extending a connection from the first exchange to the second exchange through one or more tandem exchanges, means for at times further extending said connection to a called line in the second exchange, a switch in said second exchange non-operative at said times, means for at other times controlling said switch to seize said connection, and means for transmitting impulses over said switch and said connection at said other times to control the completion of said call to one of said tandem exchanges.

14. In a telephone system, a first exchange, a second exchange, means responsive to the initiation of a call by a subscriber in said first exchange for extending a connection from said first exchange to said second exchange over a route containing one or more serially connected

trunk lines, means for at times further extending said connection to a called line terminating either in said second exchange or in a distant exchange which does not lie in and is not reached over said route, a switch in said second exchange non-operative at said times, means for operating said switch at other times to connect with the trunk line incoming to said second exchange over which said connection was extended to said second exchange, and means for transmitting impulses over said switch and said incoming trunk line at said other times to control the extension of said connection to a called line terminating either in said first exchange or in an exchange which lies in or is reached over said route.

15. In a telephone or like system, switching apparatus, two seizing paths for said apparatus, means for seizing said apparatus over one of said paths at times and transmitting thereto a certain impulse code, means for seizing said apparatus over the other of said paths at other times and transmitting thereto the same impulse code, a plurality of lines, two switches in said apparatus each having access to all of said lines, and means for causing one of said switches to seize one of said lines in response to said code if the apparatus was seized over said one path and causing the other of said switches to seize one of said lines in response to said code if the apparatus was seized over said other path.

EDUARD WOCHINGER.
